UNITED STATES PATENT OFFICE

CHARLES L. WILES, OF DETROIT, MICHIGAN, ASSIGNOR TO BUDD WHEEL COMPANY,
OF PHILADELPHIA, PENNSYLVANIA, A CORPORATION OF PENNSYLVANIA

RING FORMING MACHINE WITH KNOCK-OUT

Application filed February 2, 1928. Serial No. 251,300.

This invention relates particularly to machines for forming the rims of automobile wheels and means for feeding the machine. The machine and the means for feeding it are combined in a manner to effect automatic operation of the feeding means.

This automatic operation may be said to be a principal object of my invention.

Other objects are to secure the feeding means which will feed the work out of the machine. Such feeding means are commonly known as knock-out devices.

In the attainment of my object I make use of the approach and separation movements, particularly the separation movement, of the forming rolls of a rim forming machine to operate the feeding means. The feeding movement I carry out about one edge of the rim. I derive it by generating a torque at the same edge and in a plane at an angle to the plane of the rim. Thus it is that my invention is by nature in part a method of feeding rings from ring forming machines.

The apparatus itself embodies a fulcrum element moved into and out of engaging position through each given separation movement of the rolls and a torque applying position likewise by each separation movement of the rolls.

Other features of my invention, the objects of them, and the advantages derived through them, will be the more fully apparent upon a better understanding of its details.

In the accompanying drawings is illustrated the best form of my invention now known to me.

Figure 1 is a front elevation;

Figure 2 is a central section looking in the direction of the arrows on line 3—3 in Fig. 1;

Figure 3 is an enlarged view of the same;

Figure 4 is a horizontal section on line 4—4 of Figure 1; and

Figure 5 is an end elevation taken from the right hand end as shown by arrows 5—5 of Fig. 1.

The rolls of the machine are designated

10 and 11 and have a movement of approach

and separation as is usual in such machines by movement of their axes 12 and 13 in the axial plane 14. Either or both of the axes may be movable but certainly the lower axis 13 is movable toward and from the axis 12. 55

It is the movement of the axis 13 which is made use of to coordinate the movements of the machine with the feeding movements of the work.

Below the axis 13 and secured to the face 15 of the frame of the machine, indicated in general by the dash and dot lines, is the base frame 16 of the feeding device secured in place by bolts 17. This frame is of angle cross section in the main as shown in Figures 2 and 3. The upper face 18 of the angle cross section is arc shaped complementally to the arc of the rim to be formed and having its center lying in the plane 14 of the axes 12 and 13. The arc shaped face 18 is made removable whereby faces of different shape may be provided to accommodate rims of different size. The arrangement is such that a rim in position to be operated upon rests upon the support 18 as shown in Fig. 2. The outer edge of support 18 is beveled downwardly and outwardly for a purpose presently to appear. 70

Arranged in the axial plane 14 is the fulcrum element 19 of the feeding device. 80 This element is in the form of an oscillatable lever pivotally arranged for oscillation on an axis shaft 20 journaled in bearings 21 and 22, respectively. It is provided in its upper end with a notch 23 adapted to engage over the outer or gutter edge of a rim. The upper edge of the notch is formed by an extended bar 24 removably bolted to the upper end of lever 19 and giving it the form of a T in elevation. The under surface of the bar 24 constituting the upper edge of the notch is arc shaped in configuration in part or as a whole to conform to the arc shape of the inside of the rim. Thus, by removing it and replacing it with another of different size, fulcrum element 19 is adapted for working in conjunction with rims of various sizes. 90

Element 19 is forced toward a normal off position shown in dotted lines in Figure 5 100

by a spiral spring 25 about the axis shaft 20 and having its ends suitably connected for the purpose. The extended lower end 26 of part 19 is configured to abut against 5 the front side 27 of the angle section base 16 and thereby define its normal off position. In this position its upper end lies below the level of the support 18 and a rim being moved on that level into position to be operated upon is not interfered with by the fulcruming element 19.

The element 19 is fixed upon the shaft 20. The opposite end of shaft 20 has fixed to it a dog 28 having an operative connection with a coacting dog 29 carried from a yoke 30 bolted at 31 to the reciprocatable head 32 which carries the axis 13 of the lower roll 11. Yoke 30 moves up and down carrying the roll 11 through its approach 20 and separation movements with respect to the roll 10. So moving it carries dog 29 into and out of engagement with dog 28 and oscillates the fulcrum element 19. Dog 29 is adjustably connected with the yoke 30 through the slide 33 in jig 34, the adjustment of which is effected by a set screw 35 bearing on its upper end. It is fixed in adjusted position by bolts 36. Dog 29 is connected with the lower end of slide 33 through a knuckle joint 37 opening downwardly only against the force of a spring 38.

On the opposite side of the support 18 from the fulcruming member 19 is the torque applying element 39. This element 35 is in the form of a lever oscillatable substantially in the plane of the rim to be formed about an axis 40 at right angles to the axis 20 and located adjacent the slide 33. Like axis 20, axis 40 is mounted in the 40 base frame 16. The inner end of lever 39 underlies the same section of the rim which the fulcruming element 19 overlies, but it is normally held in a dis-engaging position shown by means of the tension spring 41 connecting it with the lower arm of the angle section of the base. The outer end of the lever 39 beyond axis 40 underlies an adjustable set screw 42 mounted upon and moving with the yoke 30.

50 The operation is as follows: A rim is fed into position to be operated upon by the rolls 10 and 11 by a feeding in mechanism of any known kind, such for example, as that shown in my co-pending application, Ser. No. 250,851, filed January 31, 1928. During this feeding in operation the fulcruming element 19 is in the dotted line position shown and it, therefore, does not interfere in any way with the movement of 55 the rim horizontally at substantially the level of the support 18, and into a position in which it rests upon that support. At this time rolls 10 and 11 are separated. Upon their approach roll 11 carries the rim so fed upwardly and into forming relation

to the roll 10. In this upward movement the dog 29 moves downwardly about its knuckle joint 37, ratcheting past the dog 28 and then straightening itself through virtue of spring 38 into a position in which it overlies the dog 28. On the downward movement of roll 11, which is the separation movement, the relative adjustment of set screws 35 and 42 is such that, first, the dog 29 engages the dog 28 and rocks the fulcruming element 19 into its full line position in which the upper end of element 19 engages over the inside of the lower section of the rim as shown clearly in Fig. 2. Immediately following this and while the uppermost end of dog 28 is in engagement with the outermost end of dog 29 and is thereby continued to be held in its full line position overlying the inner edge of the rim, the set screw 42, for the first time, engages the outer end of the lever 39 as shown in Fig. 5 and thereby swings lever 39 clockwise (from the front) about its pivotal axis 40. Its inner end, therefore, engages the under side of the same rim section engaged by the fulcruming lever 19, the entire engagement being in the plane 14 of the axes 12 and 13, and at right angles to the plane of the rim as formed. This engagement of lever 39 is a torque producing engagement, producing a torque in this section of the rim about the overlying portion 24 of the element 19 in such direction and of such force as tilts the rim about the engaged edge and thereby thrusts its upper edge outwardly as shown in dotted lines in Figure 2 and away from rolls 10 and 11. The tilting movement continues until gravity acting on the tilted rim finishes the feeding out or knock-out operation, the rim then falling about the support 18 into a horizontal position in which it is grasped by hand or else received by a suitable table conveyor (not shown).

Immediately following, the dog 29 passes the outer end of dog 28 and the fulcruming element returns to its normal off position shown in dotted lines in Figure 5 whereby as a new rim is fed into a position 18, there is again no interference. The torque producing element 39 returns to its normal position upon the institution of the approach movement of the rolls and does not, therefore, interfere with the feeding in movement of the rim. Thus the feeding in and feeding out or knock-out movements of the rim are carried out independently, except for the relation of the torque producing element 39 in motion to the feeding in motion.

The appended claims should cover all forms of my invention partaking in any wise of its generic spirit.

What I claim as new and useful is:

1. A ring knock-out mechanism comprising elements movable to engage the work on

its outer and inner surfaces and means for relatively moving said elements bodily to engage and tilt the ring.

2. A ring knock-out mechanism comprising relatively movable elements adapted to engage a determinate cross section on the ring on opposite sides thereof and means for bodily moving said elements in opposite directions, to tilt and eject the ring.

10 3. In a machine of the character described, ring forming rolls having a movement of approach and separation and a ring knock-out mechanism connected therewith and having knock-out elements engaging a determinate cross section of the ring on opposite sides thereof and in opposite directions, and means for moving at least one of said elements into engaging position through the separation movement of said

20 rolls.

4. In a machine of the character described, ring forming rolls having a movement of approach and separation and a ring knock-out mechanism connected therewith and having knock-out elements engaging a determinate cross section of the ring on opposite sides thereof and in opposite directions, and means for moving both elements into engaging position through the separation movement of said rolls.

30 5. In a machine of the character described, ring forming rolls having a movement of approach and separation and a ring knock-out mechanism connected therewith and having knock-out elements engaging a determinate cross section of the ring on opposite sides thereof and in opposite directions, means for moving both elements into engaging position through the separation movement of said rolls, and means for reversing one element to normal position through continued separation of said rolls.

40 6. A machine of the character described, ring forming rolls having a relative movement of approach and separation and a feeding mechanism for forming rings, and means for moving the feeding mechanism through said movement of approach and separation.

50 7. A ring feeding mechanism comprising fulcruming and torque applying elements engaging the ring on opposite sides, the fulcruming element of which is oscillatable into and out of the path of movement of the fed ring in one plane and the torque applying element of which is oscillatable in a different plane, and means for oscillating said elements.

In testimony whereof he hereunto affixes
55 his signature.

CHARLES L. WILES.
